METHOD OF MANUFACTURING SPOONS
OR THE LIKEJerome N. Gehred, Park Ridge, Ill., assignor to
Ekco Products Company, Chicago, Ill., a cor-
poration of Illinois

Application April 10, 1948, Serial No. 20,332

1 Claim. (Cl. 76—105)

1

The invention relates generally to the manufacture of spoons for kitchen use and more particularly to spoons made of stainless steel.

The general object of the invention is to provide a novel method of manufacturing spoons of the foregoing character, in which the waste of material is minimized and which facilitates the handling of the material throughout the various steps in the manufacture.

More specifically, it is an object to provide a novel method of manufacturing spoons of the foregoing character, by which a series of spoon blanks may remain connected to each other until the final shaping operation, thus avoiding individual handling of the blanks during preceding operations and consequently reducing the cost of manufacture.

Other objects will become apparent from the following description taken in connection with the accompanying drawing, in which:

Figure 1 is a plan view of a strip of metal having performed thereon an initial operation involved in a method embodying the features of the invention.

Fig. 2 is a transverse sectional view of the strip taken on the line 2—2 of Fig. 1.

Fig. 3 is a plan view of the strip after another operation is performed thereon.

Fig. 4 is a transverse sectional view of the strip taken on the line 4—4 of Fig. 3.

Fig. 5 is a plan view of a blank punched from the strip as shown in Fig. 3.

In making spoons, the handle portion thereof is usually substantially narrower than the bowl portion. Also, in almost all designs of spoons, the handle portion generally tapers from a maximum width at the end opposite the bowl toward the bowl so that the narrowest portion is adjacent the bowl. To give sufficient strength to the handle, particularly in its narrowest portion, a certain thickness of metal is desirable, depending upon what metal is used and the particular relative dimensions of the various parts of the spoon. Such thickness, however, is substantially greater than is necessary in the bowl portion of the spoon, and in fact an equal thickness of metal in the bowl portion of the spoon would be totally undesirable since it would make the bowl portion too heavy and the spoon would become what is termed "bowl heavy."

In the manufacture of inexpensive spoons, such as those sold for kitchen use, the spoons are made from a strip of sheet metal of uniform thickness, and punching and drawing or bending operations are employed to arrive at theulti-

mate form of the spoon. However, the difference in thickness between the bowl portion of the spoon blank and the handle portion has required the introduction, into the method of manufacturing such spoon, of the step of reducing the thickness of the metal, from the uniform thickness of the strip, in that portion ultimately forming the bowl of the spoon. It is, of course, desirable from a manufacturing standpoint to maintain the metal in its strip form as far as possible through the various steps in the manufacturing operations. The handling of individual parts involves much more time, with a consequent increase in cost, than where the parts are maintained in a continuous strip which is easily handled. Heretofore, the reduction in thickness of the metal to be used ultimately in forming the bowl has necessitated separation of the blanks from the strip form into individual blanks at an early stage in the manufacture so that such blanks have to be individually handled throughout all subsequent operations.

The method embodying the features of the invention contemplates maintenance of the blanks in the strip form through a later stage in the manufacturing operation than has heretofore been possible. In previous methods, the separation into individual blanks has occurred prior to the step of reducing the thickness of the metal in the bowl portion. By the present method, the blanks are maintained in strip form through the thickness reducing operation, and are not separated into individual blanks until just prior to the step of dishing the bowl portion and bending the handle to give it its desired curvature. The present method is particularly applicable to spoons made of stainless steel where the raw material employed in making such articles is almost invariably in sheet or strip form of uniform thickness.

To more specifically describe my improved method of manufacturing spoons, Fig. 1 of the drawing shows a strip of metal having a thickness equal to that desired for the handle portions of the spoons. Such thickness is uniform throughout the width of the strip, as clearly illustrated in Fig. 2. The width of the strip is substantially equal to the total length of one spoon plus the length of metal necessary to form a bowl portion. In addition, a slight amount of metal is allowed on each side of the strip to provide accurate trimming at the ends of the bowl portions which are closely adjacent the side edges of the strip, as is apparent in Fig. 3 of the drawings. By utilizing a strip of this width, blanks

may be punched from the strip with a minimum of scrap, as will hereinafter be apparent.

The initial step in the present method of manufacturing comprises transversely slitting, as at 10, the intermediate portion of the strip indicated at 11. The marginal portions of the strip indicated at 12 are left unslitted, as is clearly apparent in Figs. 1 and 2. The slits 10, while extending generally transversely of the strip, are curved and tapered to follow generally the outline of the handle portion of the spoon to be formed. At the ends of the slits 10, holes 13 are punched so as to prevent concentration of stresses at the ends of the slits which might result in splitting of the metal during subsequent operations. The holes 13 may, of course, be punched in the strip prior to forming the slits 10. However, both of these operations are obviously performed while the metal is in the strip form.

The next step in the present method involves reduction in the thickness of the metal to be used to form the bowl portions. As is obvious by inspection of Fig. 3, such bowl portions are punched from the marginal portions 12 of the strip. The marginal portions, therefore, are to be reduced in thickness. Since it is desired to maintain the metal in its strip form as far as possible, the reduction in thickness of the marginal portions 12 is accomplished by rolling the strip longitudinally by rolls which engage only the marginal portions 12 and do not touch the intermediate portion 11 of the strip. Such rolling of the marginal portions 12 reduces the thickness and consequently increases the length thereof.

The increase in length of the marginal portions, however, necessitates a corresponding increase in length in the intermediate portion 11 of the strip, if no buckling is to occur. The increase in length of the intermediate portion 11 follows, as a result of the elongation of the marginal portions 12, by widening of the slits 10, as indicated at 14. Since the metal in the intermediate portion 11 is not engaged by the rollers, no reduction in thickness thereof occurs and the entire increase in length is accomplished by such widening of the slits. The widening of the slits, as at 14, leaves longitudinally spaced bars of metal 15 connected at their ends to the marginal portions 12 of decreased thickness. In the preferred form of rolling, the reduction in thickness is preferably not of abrupt form but tapers gradually through a short distance, as indicated at 16 in Figs. 3 and 4.

The strip of metal is now ready for punching the spoon blanks therefrom. However, it is to be noted that it is still in strip form and that only a few operations remain to provide the finished form of spoon. All handling of the metal thus far in the process has been permitted in such strip form so that the costs of the operations thus far are substantially less than they would have been, had the metal been separated into individual blanks at an earlier stage.

In punching the blanks from the strip, I have indicated in Fig. 3, by the broken lines 17, the location of the punching to form the blanks. Thus, the bowl portions are punched from the marginal portions 12 of reduced thickness with the bowl portions of adjoining blanks taken from the opposite marginal portions. By this ar-

rangement, the metal forming the handle portions of the blank may be punched from the transverse bars 15 lying side by side. The curvature of the outline of the blank where the handle portion blends into the bowl portion follows generally the end formation of the handle portion of the adjoining blank so that there is what may be termed a nesting of the blanks, resulting in a minimum of scrap. The blank as punched from the strip in the form illustrated in Figs. 3 and 4 is shown in Fig. 5, where the handle portion is indicated at 20 and the bowl portion at 21. Such blank, of course, is flat but the bowl portion 21 is reduced in thickness relative to the handle portion 20 to the desired extent so that a spoon of proper balance may be formed therefrom. The blank illustrated in Fig. 5 is thereafter completely formed into a spoon by dishing the bowl portion 21 and bending the handle portion 20 to the extent desired.

With the foregoing method, it will be noted that the metal is maintained in the strip form through all operations except the last two comprising the punching of the blank and the final shaping thereof. This permits easy handling of the material and consequently reduces the cost of manufacture.

I claim:

30 The method of manufacturing spoons or the like from a strip of metal having a thickness equal to the thickness of the handle of the spoon and a width slightly greater than the length of a spoon plus the length of a bowl, which comprises slitting and punching the strip centrally to provide a plurality of transverse slits with enlarged holes punched at the opposite ends thereof for preventing splitting of the metal during subsequent operations, said holes being spaced from both edges of the strip a distance slightly greater than the length of the bowl to provide unslotted marginal portions on the strip and said slits being spaced longitudinally of the strip a distance slightly greater than the width of the handle, rolling the strip longitudinally along both marginal portions to reduce the thickness and increase the length thereof and to widen the slits without changing the cross-sectional form of the metal between the slits, and by said longitudinal rolling simultaneously tapering the thickness of said strip transversely thereof from said holes inwardly a substantial distance beyond the holes whereby the rolled marginal portions of the strip are gradually tapered to the full thickness of the slitted central portion of the strip and punching transversely extending spoon blanks from the strip after such rolling with the bowl portions of the blanks punched from said marginal portions and the handle portions of the blanks punched from the metal between the slits.
